DOOR OPERATION AND CONTROL

William C. Turner, Rahway, N. J., assignor, by
mesne assignments, to National Pneumatic Co.,
Inc., Boston, Mass., a corporation of Delaware

Application July 3, 1948, Serial No. 36,990

2 Claims. (Cl. 268—50)

1

This invention relates to door operation and control, and particularly to a system permitting automatic utilization of a normally inactive door operating instrumentality, in the event of temporary absence of power for energization of a second, normally active, instrumentality.

In the illustrated embodiment of the invention, the normally active instrumentality is a fluid motor having a piston assembly movable in opposite directions alternately to swing a door actuating lever to left and right, alternately, of a pivotal bearing point, and the normally inactive instrumentality is an auxiliary motor including compressible, coiled spring adapted to make automatic operative connection with said lever upon removal of fluid pressure from a supply line that is a common feeding agency for both said fluid motor and said auxiliary motor. It is to be understood, however, that the illustrated embodiment is merely an exemplification of the invention, and not a definition of the limits thereof; there being many alternative structures and arrangements possible within the principles disclosed.

An object of the invention, therefore, is to provide a lever for operating a door, to which lever two distinct operating motors are alternatively connectable; the word "lever" being employed in the broad sense of including any force-transmitting link, gear, or equivalent transmission train.

Another object is to provide, in a dual motor system of the character indicated, novel interlocking means for automatically disassociating one of the motors from the door actuating lever as the other motor becomes effective.

These and other objects of the invention will be better understood upon examination of the following description of the invention in terms of the accompanying drawings wherein:

Fig. 1 is a diagrammatic view showing two motors and a sliding type of door operable by said motors, the intervening linkage and associated control circuits, both electrical and pneumatic, being also shown;

Figs. 2 and 3 are sectioned views of the two motors, Fig. 2 showing the spring motor in its inactive position and Fig. 3 showing the motor in a position it assumes when active;

Fig. 4 is a fragmentary view showing a detail of the operating connections;

Figs. 5 and 6 are plan views of the fluid motor and door actuating lever, showing also the automatically operable clutch mechanism constituting the driving connection from the former

to the latter; Fig. 5 showing the clutch engaged to drive the lever, and Fig. 6 showing the clutch disengaged; and

Fig. 7 is a transverse view of the clutch assembly.

Referring first to Figs. 1, 2, and 3, the sliding door is shown at 11, in its closed position, the open position being indicated by the dash line 12. The fluid motor is shown at 13, 14, and 15, the numeral 13 designating the main body of the motor and the numerals 14 and 15 designating cylinders extending from opposite sides thereof. The spring motor includes a piston 16, slideable in a cylinder 17, and a piston rod 18 carrying a transverse link 19 co-acting with a longitudinal link 21, the latter having pivotal connection at 22, with a lever 23 whose opposite ends are operatively connected to motor 13 and door 11, respectively. The operative connection with door 11 takes the form of a roller 26 retained in a channel plate 27 attached to the rear vertical edge of the door, while the operative connection with motor 13 includes a clutch mechanism having a driving element 31 (Figs. 5, 6, 7) and a driven element 32, the latter being an integral part of a plate 33 bolted to lever 23, and driving element 31 being internally splined to slide on splined shaft 34 which is journaled in the bearing elements 36, 37 (Figs. 5 and 6) of the motor body 13, and carries the sector gear 36 (Fig. 3) which meshes with rack 37 of the piston assembly 38, 39.

The novel means for inter-locking motors 13 and 17, so that one remains inactive when the other is effective, comprises a pin-and-slot connection between links 19 and 21, and also a pin-and-rocker connection between links 19 and 41, the latter having connection, at its opposite end, with a bell crank 42 (Figs. 5, 6, 7) extending from clutch yoke 43; yoke 43 being the agency for shifting clutch element 31 into driving engagement with clutch element 32, when the parts are in the relationships indicated in Fig. 2, that is, the pin 46 being held firmly against the rocker 47 by the pressure of the fluid acting upon piston 16, such fluid being admitted to the cylinder 17 by way of port 48, to which port the fluid supply line 49 (Fig. 1) connects.

The fluid supply lines 49, 51, 52, are shown in Fig. 1 as being under the control of a valve 53 which is spring-biased to a fluid exhausting position but shiftable to a fluid feeding position (the line 54 being the source of pressure fluid) upon flow of electric current to the solenoid 56, the latter being in a circuit that is normally con-

connected to a current source 57 by way of a normally closed switch 58. A second valve 61 (Fig. 1) is spring-biased to a position establishing communication between supply line 52 and a connecting line 62 leading to port 63 (Fig. 3) at the right end of cylinder 15 of fluid motor 13. However, upon flow of current to solenoid 64, the valve 61 shifts to a position cutting off communication between lines 52 and 62, and connecting line 62 to the atmosphere, thus exhausting all fluid from cylinder 15. The pressure normally in line 51, on the other hand, is exerted against piston 38, as the line 51 connects with cylinder 14 by way of port 63 (Fig. 3).

In normal operation, a person desiring passage through the door-way closes switch 64 (Fig. 1) located at some convenient point, for example, behind the hand-grip 66 of the door. Closure of switch 64 causes a flow of current from source 57 to the winding of relay 67, by way of conductors 68 and 69. Energization of the relay winding, though only momentary, is sufficient to move the bridging members 71 and 72 into their contact bridging positions, which bridging relationships continue by reason of the self-holding action of the relay, that is, the flow of current to the winding of the relay continues by way of conductors 73, 74, 76, and 69, and the now closed switches 71 and 75, forming part of this self-holding circuit of the relay.

As the switch 72 moves to its bridging position, current flows to solenoid 64, the current path being by way of conductor 73, switch 72, and conductor 77. Energization of solenoid 64 shifts valve 61 to the fluid discharging position, thereby exhausting all pressure from cylinder 15. Exhaust of pressure from cylinder 15, while cylinder 14 remains under full line pressure, by reason of the connection of supply lines 54 and 51 therewith, permits rack 37 to move to the right, thus swinging sector gear 40 and lever 23 in a counter-clockwise direction, the drive from member 40 to member 23 being by way of clutch parts 31 and 32, now engaged, as the pin 46 is in the position indicated in full lines in Fig. 5, being held in such position (see also Fig. 2) by the pressure of the fluid entering port 48 (from line 49, Fig. 1) and acting upon piston 16 of the spring motor 17.

The resulting counter-clockwise swing of lever 23 carries door 11 to the fully open position indicated by the dash line 12 in Fig. 1. As the door reaches this open position striker 70 engages switch 75 and moves it to a current-interrupting position, compressing the spring 81 which normally maintains the switch 75 closed. This interruption of the self-holding circuits stops the flow of current to relay winding 67 and (allowing for a few seconds of delay, if the relay is of the delayed-return type) the switches 71 and 72 will now return to the circuit-open positions illustrated in Fig. 1. Flow of current to solenoid 64 is thus interrupted (at switch 72) and the valve 61 shifts back (because of its spring bias) to the fluid-feeding position. Pressure fluid, therefore, again enters the cylinder 15; and as the piston 39 is of greater area than piston 38, the resulting pressure differential will cause rack to move back to its extreme left position, that is, the position shown in Fig. 3.

This leftward shift of rack 37 will return door 11 to the closed position (full lines, Fig. 1), in which position it will remain until there is another occasion for it to be opened.

If for any emergency reason, the normally

closed switch 58 were to be thrown to circuit-opening position, or if there should be a failure of electric power at the source 57, the resultant de-energization of solenoid 56 will allow valve 53 to exhaust to the atmosphere all the fluid under pressure in the cylinders 14 and 15 of motor 13, as well as the fluid under pressure in cylinder 17 of the spring motor. Piston 16 of said spring motor will thereupon be urged, by spring 20, into the position shown in Fig. 3, in which position pin 85 of link 19 will engage the forward end of the slot in link 21, and pin 46 of link 19 will assume the relative position indicated in dash lines in Fig. 5 and Fig. 6, in which position it no longer presses upon rocker 47, hence the clutch shifting spring 90 (Figs. 5 and 6) is now effective to shift the clutch part 31 to the disengaged position shown in Fig. 6; such shift causing the link 41 and rocker 47 to shift, also, into the positions indicated in Fig. 6. The door lever 23 is thus freed from the restraint of the parts of motor 13, and on the next opening of door 11 (manually, in view of the removal of fluid pressure) the lever 23 will swivel freely on the outer (un-spined end of the shaft 34. However, on such opening swing, lever 23 will move link 21 along with it, thus carrying link 19 and piston 16 to the left of the positions indicated in Fig. 3, and into the positions shown in Fig. 2, in which latter positions the spring 20 is compressed, and therefore ready to produce an automatic re-closing of the door as soon as the latter is released by the person who opened it; the expanding spring 20 being effective to close the door by direct action on links 19 and 21, and lever 23, independently of the now idle clutch part 31.

The length of cylinder 17, in relation to the swing of lever 23, is such that the door is fully closed against the door jamb while piston 16 is still some slight distance short of contact with the cylinder end wall, hence there is continuing spring pressure acting upon the door, through the piston and linkage, so that any tendency of the door to vibrate away from its jamb position is constantly resisted by the spring 20. In other words the cylinder and linkage are so proportioned as to assure continuous spring pressure to hold the door firmly closed, when no air pressure is available for that purpose.

On the other hand, when air pressure is available, the door is held firmly closed by the pressure differential existing in favor of the larger piston 39. However, this differential is purposely made not too great, so that a temporary halt of the door while closing (such as might result from an obstruction in the door way) will not permit the building up of an excessive closing pressure differential and therefore there will be no "slamming" tendency when the door resumes its closing movement, upon release of the obstruction.

It will be observed that clutch parts 31, 32 have only one angular position in which the tooth of part 32 will register with the notch in part 31, hence the rack 37 and the lever 23 must be in correctly synchronized positions before meshing of the clutch parts can occur. This insures proper operation of the doors on each resumption of fluid power operation.

What I claim is:

1. Door operating means comprising a lever pivotally mounted for swinging in an arc, the free end of said lever being connected to the door to move the latter from a closed position to an open position as the lever swings through its arcuate

path, a slotted link pivotally connected to said lever intermediate its ends, a first power unit including cylinder having a spring-biased piston therein, a piston rod attached to said piston, a control arm projecting from said rod, said control arm carrying an element movable along the slotted portion of said link in response to motion of said piston, a second power unit including a shaft and a clutch driven by said shaft, the driven element of said clutch being operatively connected to said lever to move it through said arcuate path, means operated by said control arm for holding said clutch engaged, so long as fluid pressure is acting upon said piston, and resilient means for disengaging said clutch upon release of said fluid pressure.

2. Door operating means comprising a lever pivotally mounted for swinging in an arc, the free end of said lever being connected to the door to move the latter from a closed position to an open position as the lever swings through its arcuate path, a first power unit including cylinder having a spring-biased piston therein, a piston rod attached to said piston, a control arm projecting from said rod, a second power unit including a shaft and a clutch driven by said shaft, the driven element of said clutch being

operatively connected to said lever to move it through said arcuate path, means operated by said control arm for holding said clutch engaged, so long as fluid pressure is acting upon said piston, and resilient means for disengaging said clutch upon release of said fluid pressure.

WILLIAM C. TURNER.
